HERBERT A. WALLACE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 17, 1925. Serial No. 50,607.

My invention relates to railway traffic controlling apparatus, and particularly to apparatus of the type comprising train carried governing means controlled in accordance with traffic conditions in advance of the train.

More specifically, my invention relates to apparatus of the type comprising automatic mechanism on the train for causing an automatic application of the brakes under unsafe traffic conditions. One feature of my invention is the provision in a system of this type of means for rendering the automatic brake applying mechanism ineffective under unsafe traffic conditions provided both the fireman and the engineman take suitable action.

I will describe two forms of railway traffic controlling apparatus embodying my invention, and will then point out the novel features thereof in claims.

In the accompanying drawing, Fig. 1 is a view, partly diagrammatic, showing one form of railway traffic controlling apparatus embodying my invention. Fig. 2 is a view showing a modified form of the apparatus illustrated in Fig. 1 and also embodying my invention.

Similar reference characters refer to similar parts in both views.

Referring first to Fig. 1, the reference character A designates a brake valve comprising a valve body 4 containing two chambers 5 and 6. Chamber 5 is constantly connected with atmosphere. Chamber 6 communicates with a pipe 1 which is normally supplied with fluid pressure and which is arranged to apply the brakes when pressure in this pipe is reduced. Valve A also comprises a plunger 2 provided with an armature 7. Associated with this plunger is a winding 8. This winding is controlled in accordance with traffic conditions in advance by means which form no part of my present invention and which are omitted from the drawing for the sake of simplicity. For present purposes it is sufficient to state that under safe, or proceed, traffic conditions winding 8 is energized, but that under unsafe, or stop, traffic conditions winding 8 is de-energized. The plunger 2 is constantly urged upwardly by a spring 3 and when plunger 2 is in its upper position pipe 9 is connected with chamber 6. When winding

8 is energized armature 7 is drawn downwardly and plunger 2 then disconnects pipe 9 from chamber 6 and connects this pipe with chamber 5 and hence with atmosphere. Pipe 9 is connected with a reservoir 15 when the suppressing valve B is open. It follows that when winding 8 of valve A is energized and when valve B is open, reservoir 15 is connected with atmosphere through valve A and pipe 1 is blanked so that an automatic application of the brakes is prevented. If, however, winding 8 becomes de-energized, pipe 1 is connected with reservoir 15 through pipe 9, thereby decreasing the pressure in pipe 1 and causing an automatic application of the brakes.

The suppressing valve B comprises a chamber 11 and a flexible diaphragm 12 which is subjected to the fluid pressure in this chamber. A plunger 13 is controlled by the diaphragm 12 and this plunger in turn carries a piston 14 and a pin valve 40. The plunger 13 is normally biased, by a spring 10, to a lower position wherein pipe 9 is connected with reservoir 15 and valve 40 is closed. When fluid pressure is supplied to chamber 11, diaphragm 12 is moved upwardly, lifting piston 14 and valve 40 to their upper positions. Reservoir 15 is then disconnected from pipe 9 and fluid pressure is supplied to this reservoir from a source not shown in the drawing through pipe 41 and valve 40. If under these conditions winding 8 of valve A becomes de-energized an automatic application of the brakes cannot result because pipe 9 is blanked by piston 14.

The suppressing valve B is controlled by two acknowledging valves C and D which are located in such positions in the locomotive cab that they may be conveniently operated by the engineman and fireman, respectively. The engineman's acknowledging valve C comprises a valve body C² and a movable valve member C'. Similarly, the fireman's acknowledging valve D comprises a valve body D² and a movable valve member D'. As shown in the drawing both the engineman's acknowledging valve C and the fireman's acknowledging valve D are in their normal positions. With the apparatus in this condition fluid pressure is supplied from a suitable source not shown in the drawing through pipe 20, valve C, pipes 19 and 19^a,

check valve 21, pipe 22, valve D and pipe 23 to an acknowledging reservoir 24. The acknowledging reservoir is therefore charged with fluid pressure. If it is desired 5 to operate the suppressing valve B to prevent an automatic application of the brakes, the engineman reverses valve C and the fireman reverses valve D. The reversal of valve C disconnects pipe 19 from pipe 20 and connects pipe 19 with pipe 17. The reversal of valve D disconnects pipe 23 from pipe 22 and connects pipe 23 with pipe 25. Fluid pressure is therefore supplied from 10 the acknowledging reservoir 24, through pipe 23, valve D, pipe 25, check valve 26, pipes 27 and 19, valve C and pipe 17 to chamber 11 of suppressing valve B. The pressure thus supplied to chamber 11 lifts 15 the diaphragm 12 to close the suppressing valve B, thereby disconnecting reservoir 15 from pipe 9 and charging this reservoir with fluid pressure. With the apparatus in this condition an automatic application of the 20 brakes is prevented even though winding 8 of valve A should become de-energized. The pressure in reservoir 24 and chamber 11 is gradually dissipated to atmosphere through a restricted orifice 16 in valve B, so that after a time interval the pressure in 25 chamber 11 is reduced sufficiently to permit spring 10 to restore plunger 13 to its lower position.

Pipe 1 will then be connected with reservoir 15 through pipe 9, but reservoir 15 30 has been previously charged with fluid pressure and therefore this operation of valve B does not cause a reduction in the pressure in pipe 1. If, therefore, the suppressing valve B is operated prior to the de-energization of valve A, an automatic application 35 of the brakes is prevented even though valve B subsequently returns to its original position and even though valve A remains in its de-energized condition.

If valve C is in its normal position and valve D is in its reverse position, check 40 valve 26 prevents the supply of fluid pressure to reservoir 24 and valve C prevents fluid pressure which may exist in reservoir 24 from being supplied to chamber 11 of valve B. On the other hand, if valve C is in the reverse position and valve D is in the normal position valve C prevents the supply of fluid pressure to the reservoir 24 and check 45 valve 21 prevents the supply of fluid pressure from acknowledging reservoir 24 to chamber 11 of valve B. It will therefore be plain that in order to charge acknowledging reservoir 24, both valves C and D 50 must be in their normal positions, and in order to operate valve B by pressure in the acknowledging reservoir, both valves C and D must occupy their reverse positions. The apparatus therefore insures that both the 55 engineman and the fireman are alert because

if either fails to operate his acknowledging valve at the proper time, the suppressing valve B cannot be operated to prevent an automatic brake application should valve A become open.

Referring now to Fig. 2, the brake valve A and the suppressing valve B are similar to the corresponding parts shown in Fig. 1 with the single exception that the restricted port 16 is omitted from valve B. The acknowledging valves C and D are illustrated in their normal positions, wherein chamber 11 of valve B is connected with atmosphere through pipe 17, port 32 of valve C, and a restricted orifice 33, so that valve B is open. Under these conditions also, fluid pressure is supplied from pipe 20, through port 28 of valve C, pipe 29, port 30 of valve D and pipes 31 and 23 to acknowledging reservoir 24. This reservoir is therefore charged with fluid pressure. I will now assume that valves C and D are moved to their reverse positions. Pipe 20 is then disconnected from pipe 29 and pipe 29 is connected with port 33. At the same time pipe 35 is connected with pipe 17 by means of port 34 of valve C. The reversal of valve D connects pipe 31 with a restricted orifice 36 by means of port 30 of valve D, and connects pipe 23^a with pipe 35 by port 38 of valve D. Pressure in acknowledging reservoir 24 then flows through pipes 23 and 23^a, port 38 of valve D, pipe 35, port 34 of valve C and pipe 17 to chamber 11 of suppressing valve B. Diaphragm 12 is therefore lifted, moving plunger 13 upwardly to disconnect pipe 9 from reservoir 15 and charge this reservoir with fluid pressure. The pressure in reservoir 24 also flows through pipes 23 and 31, port 30 of valve D and restricted orifice 36 to atmosphere. After a time interval, therefore, the pressure in 105 reservoir 24 and chamber 11 is so reduced by dissipation to atmosphere through port 36 that spring 10 restores plunger 13 to its lower position and again connects pipe 9 with reservoir 15.

I will assume that valves C and D both occupy their normal positions so that reservoir 24 is charged with fluid pressure, and that the engineman reverses his acknowledging valve C, but that the fireman leaves the valve D in its normal position. The reversal of valve C connects pipe 17 with pipe 35, but pipe 35 is connected with atmosphere at orifice 36 by means of port 37 in valve D and therefore no pressure is supplied to chamber 11 of valve B. The reversal of valve C also connects pipe 29 with restricted orifice 33 and pressure from reservoir 24 therefore flows through pipes 23 and 31, port 30 of valve D, pipe 29, port 28 of valve C and restricted orifice 33 to atmosphere. The pressure in acknowledging reservoir 24 is therefore slowly dissipated to

atmosphere. If the fireman moves the valve 5 D to the reverse position before the pressure in reservoir 24 is reduced below a given value, this pressure will be supplied to 10 chamber 11 of valve B as already described, and will operate this valve for a time interval. It should be noted however that the time during which valve B is closed depends upon the length of time necessary to reduce 15 the pressure in chamber 11 to the value which will allow spring 10 to move plunger 13 downwardly against the pressure in chamber 11. It will also be noted that the pressure in reservoir 24 commences to decrease as soon as valve C is reversed and that therefore the time interval during which the suppressing valve can be held closed commences when the valve C is reversed although the valve B does not operate until 20 valve D is also reversed.

I will now assume that the fireman reverses valve D, but that the engineman leaves valve C in the normal position. The reversal of valve D disconnects pipe 29 from pipe 31 and connects pipe 31 with restricted orifice 36. Pressure from reservoir 24 therefore gradually leaks off through pipes 23 and 21, port 30, of valve D and restricted orifice 36. Although valve D is reversed, connecting pipe 23 with pipe 35, pressure from reservoir 24 can not flow into chamber 11 of valve B because pipe 35 is blanked at valve C. If now, the engineman should reverse valve C the pressure in reservoir 24 is supplied to chamber 11 but this pressure has been reduced by dissipation to atmosphere through orifice 36 of valve D, below the value to which the reservoir 24 was initially charged.

It will therefore be clear that the reversal of either valve D or C commences the discharge of the reservoir 24, which discharge requires a time interval. If, before this time interval elapses, the other acknowledging valve is reversed, valve B will be operated and will return to its normal position at the end of this interval.

One advantage of my invention is that the engineman and the fireman must both take suitable action upon a change from safe to dangerous traffic conditions and that unless they take such action an automatic application of the brakes will be incurred.

Although I have herein shown and described only two forms of railway traffic controlling apparatus embodying my invention, it is understood that various changes and modifications may be made therein within the scope of the appended claims without departing from the spirit and scope of my invention.

Having thus described my invention what I claim is:

1. In combination on a train, automatic brake applying mechanism responsive to

traffic conditions in advance of the train, two separate manually operable acknowledging valves, and means effective only upon operation of both said valves for rendering said automatic mechanism ineffective to apply the brakes.

2. In combination on a train, automatic brake applying mechanism responsive to traffic conditions in advance of the train, two separate manually operable acknowledging valves, and means controlled jointly by said valves for rendering said automatic mechanism ineffective to apply the brakes.

3. In combination on a train, automatic brake applying mechanism responsive to traffic conditions in advance of the train, two separate manually operable acknowledging valves, and means effective for a time interval after both said valves are operated for rendering said automatic mechanism ineffective to apply the brakes.

4. In combination on a train, automatic brake applying mechanism responsive to traffic conditions in advance of the train, a suppressing valve arranged to render said automatic mechanism ineffective to apply the brakes when said valve is supplied with fluid pressure, two separate manually operable valves, a reservoir, means effective when both said valves are in their normal positions for charging said reservoir with fluid pressure, and means effective when both said valves are in their reverse positions for connecting said reservoir with said suppressing valve.

5. In combination on a train, automatic brake applying mechanism responsive to traffic conditions in advance of the train, a suppressing valve comprising a chamber and means for rendering said automatic mechanism ineffective to apply the brakes when said chamber is supplied with fluid pressure, a pipe, a source of fluid pressure, a first manually operable valve for connecting said pipe with said chamber or with said source depending upon the position of such valve, a reservoir, and means including a second manually operable valve for permitting the flow of fluid pressure from said pipe to said reservoir or from said reservoir to said pipe depending upon the position of said second manually operable valve.

6. In combination on a train, automatic brake applying mechanism responsive to traffic conditions in advance of the train, a suppressing valve comprising a chamber and means for rendering said automatic mechanism ineffective to apply the brakes when said chamber is supplied with fluid pressure, two separate manually operable valves each capable of a normal or a reverse position, a reservoir, a source of fluid pressure, and means for connecting said source with said reservoir when both said valves are in their normal positions but for con-

necting said reservoir with said chamber when both said valves are in their reverse positions.

7. In combination on a train, automatic 5 brake applying mechanism responsive to traffic conditions in advance of the train, a suppressing valve comprising a chamber and means for rendering said automatic mechanism ineffective to apply the brakes when 10 said chamber is supplied with fluid pressure, a pipe, a source of fluid pressure, a first manually operable valve for connecting said pipe with said chamber or with said source depending upon the position of such valve, 15 a reservoir, a second manually operable valve capable of a normal or a reverse position, a first check valve for permitting the flow of fluid pressure from said pipe to said reservoir when said second manually operable 20 valve is in its normal position, and a second check valve for permitting the flow of fluid pressure from said reservoir to said pipe when said second manually operable valve is in the reverse position.

25 8. In combination on a train, automatic brake applying mechanism responsive to traffic conditions in advance of the train, suppressing means including a chamber and arranged to render said automatic mechanism ineffective to apply the brakes when 30 said chamber is supplied with fluid pressure, a reservoir, two separate manually operable valves each capable of a normal or a reverse position, means effective when both said 35 valves are in their normal positions for charging said reservoir with fluid pressure, means effective when either said valve is in its reverse position for connecting said reservoir with atmosphere through a restricted orifice, and means effective when 40 both said valves are in their reverse positions for connecting said reservoir with said chamber.

45 9. In combination, on a train, automatic brake applying mechanism responsive to traffic conditions in advance of the train, suppressing means including a chamber and arranged to render said automatic mechanism ineffective to apply the brakes when 50 said chamber is supplied with fluid pressure, a reservoir, two separate manually operable valves each capable of a normal or a reverse position, means effective only when both 55 said valves are in their normal positions for charging said reservoir with fluid pressure, means effective when either said valve is in its normal position for connecting said chamber with atmosphere, means effective when either said valve is in its reverse position 60 for connecting said reservoir with atmosphere through a restricted orifice, and

means effective when said valves are both in their reverse positions for connecting said reservoir with said chamber.

10. In combination on a train, automatic 65 brake applying mechanism responsive to traffic conditions in advance of the train, suppressing means including a chamber and arranged to render said automatic mechanism ineffective to apply the brakes when 70 said chamber is supplied with fluid pressure, two separate manually operable valves and means effective when both said valves are operated for actuating said suppressing means for a time interval, said time interval 75 commencing when either of said valves is operated.

11. In combination on a train, automatic 80 brake applying mechanism responsive to traffic conditions in advance of the train, two separate manually operable acknowledging valves, and means effective only upon operation of both said valves for rendering said automatic mechanism ineffective for a 85 time interval which commences when either one of said valves is operated.

12. In combination on a train, automatic 90 brake applying mechanism responsive to traffic conditions in advance of the train, a suppressing valve comprising a chamber connected with atmosphere through a restricted orifice and means for rendering said 95 automatic mechanism ineffective to apply the brakes when said chamber is supplied with fluid pressure, two separate manually operable 100 valves, a reservoir, means effective when both said valves are in their normal positions for charging said reservoir with fluid pressure, and means effective when both said valves are in their reverse positions for 105 connecting said reservoir with said chamber.

13. In combination on a train, automatic 110 brake applying mechanism responsive to traffic conditions in advance of the train, two separate manually operable acknowledging valves, and means effective upon operation of both said valves within a time interval which commences when either such valve is operated for rendering said automatic apparatus ineffective to apply the brakes.

14. In combination on a train, automatic 115 brake applying mechanism responsive to traffic conditions in advance of the train, two separate manually operable acknowledging valves, and means effective upon operation of both said valves within a time interval which commences when either such valve is operated for rendering said automatic apparatus ineffective to apply the brakes until said interval has elapsed.

In testimony whereof I affix my signature.
HERBERT A. WALLACE.
